UNITED STATES PATENT OFFICE.

HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY.

SIFTER TOP FOR RECEPTACLES.

Application filed March 27, 1926. Serial No. 97,894.

This invention is an improvement in tops for receptacles, and more particularly in sifter tops for powder containers.

In the usual construction of sifter top, a plurality of openings is provided, covered and uncovered by a valve plate, having openings to register with those of the top. The valve plate is movable with respect to the top to bring the openings thereof into and out of register with those of the top, and the said plate is usually mounted on the inner face.

The construction is objectionable for many reasons. Loss may occur and contamination of the contents result through inadvertent failure to close the valve plate after use. There is always the liability that the connection between the top and the valve plate may become loose with consequent leakage and contamination.

When the valve plate is on the inner face, the contents of the container, and particularly powder, tend to enter between the plate and the cover, thus to clog the free movement of the plate, and if the plate is on the outer face of the top it is liable to be torn off, bent out of shape, or its proper functioning otherwise impaired.

It is desirable that the valve plate be normally urged or biased to closed position, in order to insure closing after use. It is also desirable that the outer surface of the top be plain and smooth, without projections, depressions or angles to catch and hold foreign bodies, dirt and the like, particularly with cans designed for holding toilet articles for babies, thus to eliminate the possibility of injury to the child.

One of the primary objects of the present invention is to provide a top of the character specified, wherein the valve plate is enclosed in a chamber entirely outside of the can and communicating with the interior only through the sifter openings.

A further object is the provision of a cover wherein the valve plate and its enclosing chamber are so constructed as to prevent as completely as possible access of the powder contents of the can to the chamber.

Another object is the provision of a cover wherein the valve plate is normally urged or biased to closed position, and wherein the operating mechanism therefor while accessible from the exterior is of a character

such that it cannot cause injury to a child. 55

A further object is the provision of a cover assembly including a valve plate, capable of attachment to the neck or body of a can, after filling.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention. 70

In the drawings forming a part hereof:

Fig. 1 is a section on the line 1—1 of Fig. 2.

Fig. 2 is a bottom plan view of the inner member of the top. 75

Fig. 3 is a perspective view showing the several elements of the cover or top separated from each other.

Fig. 4 is an enlarged detail in section of a part of the inner member of the top. 80

In the present embodiment of the invention, the improvement consists of a pair of nested substantially cup or dome shaped members 1 and 2, the member 2 fitted closely within the member 1. The flanges of the members are of substantially the same depth, so that when the member 2 is fitted within the member 1 the free edges of the flanges will be substantially flush. 85

Each of the members has a plurality of openings or perforations, 3 for the member 1, and 4 for the member 2, and the said openings or perforations of the two members are in register, and preferably in annular formation as shown. The central portion of the member 2 over an area of circular shape is offset laterally away from the member 1, as indicated at 5, to form between the two members a chamber for receiving the valve plate 6. 90

The plate 6 is circular in outline, and it is pivoted in the chamber on a central axis, to rotate therein. The plate has a central opening 7, through which extends a boss 8 on the inner member 2, and the boss is of a height sufficient to pass through the central opening 7 and engage within a boss 9 on the outer member. The plate 6 has open- 105

ings or perforations 10 corresponding in size, arrangement and spacing with the registering openings 3 and 4 of the members, and the said openings 10 are designed to register with the registering openings to permit discharge of the contents of the container.

The plate is provided with a radial arm 11 which forms a handle for manipulating 10 the same. Referring to Fig. 1 it will be seen that the top taken as a whole is dome shaped or convex externally, and the plate 6 is shaped in like manner. The handle extends between the members to and through 15 a circumferential slot 12 in the outer member, and the free end thereof outside the slot is cupped or bossed as shown at 13 to provide a species of button or knob for convenience in manipulating the same.

20 The inner member 2 has a substantially radial groove 14 in which the handle lies, and the groove is of sufficient width to permit the lateral movement of the handle to cover and uncover the perforations of the 25 members 1 and 2. A spring is provided to normally urge or bias the valve plate to closed position. This spring consists of two arms extending at an acute angle, and one of the arms 15 is held beneath struckup 30 spurs or lugs 16 on the inner member. The other arm 17 engages a notched lug 18 on the plate 6, the lug moving in an arc shaped slot 19 in the inner member. The arrangement of the spring is such as to normally 35 urge the lug toward one end of the slot and in a direction to move the plate into closed position.

In order to make a close seal at the perforated portion of the top, to prevent the entrance of foreign matter and the escape of 40 the container's contents, the inner member 2 is provided with an annular groove 20 near the junction of the offset portion 5 with the body of the member, and the valve plate 6 45 has an annular rib 21 fitting within the groove. The rib and groove provide a seal between the valve plate and the inner member at the periphery of the valve. Since the rib and groove are circular, it is obvious 50 that they assist in the pivotal mounting of the valve plate. In fact the bosses 8 and 9, and the opening 7 might be dispensed with, the rib and groove serving the purpose.

The flanges of the members 1 and 2 are in 55 close contact and the said flanges engage outside the top of the container or about a neck on the same. The flange of the inner member fits the container or neck closely, and the flange of the member 1 fits the flange of 60 the member 2 closely. The containers may be filled from the top in the usual manner, before the tops are placed, and the tops may be held by friction, by bosses, or in any other suitable manner.

65 What is claimed as new is:

1. A top for can bodies including a pair of substantially cup or dome shaped members nested one within the other with the side walls thereof in close engagement and of substantially the same depth and adapted 70 to engage about the top of the body to form a cover therefor, the members having registering perforations, a plate having perforations spaced to register with those of the members, said members shaped to provide a 75 plate receiving chamber between them of an area corresponding substantially to that of the plate and of a size to permit guided movement of the plate in the chamber, a handle on the plate, the outer member 80 slotted for the passage of the handle, and resilient means acting normally to hold the plate with the perforations thereof out of register with those of the members.

2. A top for can bodies, flanged and designed to engage about the end of a can body to form a top therefor, said top including nested substantially dome shaped members fitting closely throughout at the flange, the flanges of substantially the same depth, and the members spaced apart about their center to form a valve plate receiving chamber, a plate rotatable in the chamber, the members and the plate having perforations registering when the plate is in one position, 90 and out of register when the plate is in another position, means to normally hold the plate in said other position, and means to move the plate.

3. A top for can bodies, flanged to engage about the open end of a can body to form a top therefor, said top including nested substantially dome shaped members fitting closely throughout the flanges, the flanges of substantially the same depth and the members spaced apart about their common center to form a valve plate receiving chamber, a plate rotatable in the chamber, the members and the plate having perforations registering when the plate is in one position, 100 and out of register when the plate is in another position, means to move the plate, the plate and the inner member having an interfitting rib and groove of annular outline outside the perforations and concentric with the axis of rotation of the plate.

4. A top for can bodies, flanged to engage about the open end of a can body to form a top therefor, said top including nested substantially dome shaped members fitting closely throughout the flanges, the flanges of substantially the same depth and the members spaced apart about their common center to form a valve plate receiving chamber, a plate rotatable in the chamber, the members and the plate having perforations registering when the plate is in one position, 110 and out of register when the plate is in another position, means to move the plate, the inner member having an annular groove 115 120 125 130

near the edge of the plate and outside the perforations, and the plate an annular rib fitting within the groove.

5. A top for can bodies, flanged to engage about the open end of a body to form a top therefor, the top including nested substantially dome shaped members fitting closely throughout the flanges, the flanges of substantially the same depth, and the members spaced apart about their common center to form a valve plate receiving chamber, and a plate rotatable in the chamber, the inner member having an annular groove near the edge of the plate and concentric with the axis of rotation thereof, the plate having an annular rib fitting and moving within the groove.

6. A top for can bodies, flanged to engage about the open end of a can body to form a top therefor, said top including nested substantially dome shaped members fitting closely throughout the flanges, the flanges of substantially the same depth and the members spaced apart about their common center to form a valve plate receiving chamber, a plate rotatable in the chamber, the plate having a handle and the outer member an arc shaped slot through which the handle extends, the handle lying closely against the outer face of the outer member at its edges for the purpose specified.

Signed at Baltimore, in the State of Maryland, this 24th day of March, A. D. 1926.

HENRY HERMANI.
